UNITED STATES PATENT OFFICE.

LAWRENCE A. McCARTHY, OF BROOKLYN, NEW YORK.

MULTIPLEX-TELEGRAPH CIRCUIT.

SPECIFICATION forming part of Letters Patent No. 700,800, dated May 27, 1902.

Application filed November 18, 1901. Serial No. 82,712. (No model.)

To all whom it may concern:

Be it known that I, LAWRENCE A. McCARTHY, a citizen of the United States of America, residing at 1059 Bedford avenue, Brooklyn, 5 New York, have invented new and useful Improvements in Multiplex-Telegraph Circuits, of which the following is a specification.

The object of this invention is to combine with the receiving instruments and controlling device at the one end of a quadruplex-telegraph circuit, as shown in Patent No. 693,530, allowed me February 18, 1902, shunting-magnets, so arranged that the incoming current from the distant end of the circuit 15 will not be able to interfere with or change the resistance of the artificial line, and thereby throw the receiving instruments out of balance and cause them to record false or mutilated signals.

20 I attain the object of my invention by the combining with the controlling and receiving instruments in the main and artificial line at the home station of a non-polarized electromagnet having a single winding the separated coils of which are inserted one in the main and the other in the artificial line and are arranged to act in an opposite direction on an armature common to both, drawing said armature to either the one side or to the other side, pressing 25 one or the other of the contact-arms away from the central contact-stop, thereby breaking and keeping open the local circuit on the controlling instrument as long as one of the magnets of the shunting - relay is enough 30 stronger than the other magnet to overcome the retractile springs, which are adjusted to a prearranged strength, as hereinafter set forth.

Referring to the accompanying drawings, which are made a part of this specification, 35 Figure 1 gives a general outline of the arrangement and connections of the receiving and controlling instruments in the main and artificial line and the local circuit of the controlling instrument at the one end of a circuit and shows a dynamo or source of power at the other or distant end of the circuit. and thereby the stronger side instead of swinging from side to side on each reversal of the current through said coils, as would be the case were the needle permanently magnetized. Now assuming that retractile springs j and j' (shown in Fig. 1) have been adjusted so that contact-arms h and h' cannot be drawn away from post l by less than an excess of one-fourth of the full strength of the main battery passing through one side more than through the other side of the circuit the action of different currents passing through the magnets $S R$ and $S R'$ of the shunting-relay and through coils C and C' of the controlling instrument and their action with or on each other and on the rheostat or artificial line is substantially as follows: With the distant end of the main line to ground the current from the home battery would divide, going to the line on the one side and to the ground through the rheostat on the other side, and if the resistance in the rheostat equaled the resistance of the main line the current from the battery would divide equally through each side and have equal effect on armature sa or needle N ; but if the line had, say, a resistance of three thousand five hundred ohms and the rheostat a resistance of four thousand ohms there would more current go through the main line than through the artificial line, and while this difference in strength of current would not be great enough to enable shunting-magnet $S R'$ to attract armature S with sufficient strength to cause it to overcome spring j' and press contact-arm h' away from post l it would be great enough to cause mutilated signals by the receiving instruments and would also be great enough to cause coil C' of the controlling instrument to attract the lower end of needle n and causing its upper end to swing against stop s , closing the local circuit through m' and cause rheostat R to act and its resistance to be changed until it equaled the resistance of the line, when coils C and C' , having regained equal strength, would have an equal attractive power over needle n and draw it again to a central position and break the local circuit. Now with both branches of the circuit of equal resistance if a positive current of a certain strength be sent to line from the home battery and a negative current of equal strength be sent to line from the distant station the effect would be to double the attractive power of magnet $S R'$ and coil C' , causing armature S to be strongly drawn against arm h' , pressing it away from stop l and open the local circuit shown from needle n through arm h , stop l , arm h' , local battery LB , and magnet m' to stop s and preventing needle n from closing said circuit by being drawn against stop s , and thus preventing rheostat R from being actuated and the resistance in the artificial line from being changed or with the positive current from the home battery remaining to line and the current at the distant end being reversed, sending a current of positive polarity to line,

the result would be to neutralize the magnetizing effect of each other on magnet $S R'$ and allow magnet $S R$ to attract armature sa and cause it to press contact-arm h away from post l , breaking the local circuit as before and preventing needle n from acting on magnet m by being drawn toward coil C and against stop s' and through it on rheostat R . Therefore, as long as a current is sent from the distant station the effect will be to cause magnet $S R$ or $S R'$ to act on armature sa , causing it in turn to act against contact-arms h or h' and prevent coils C C' and needle n from being able to have any effect on or control over magnets m or m' and through them on automatic rheostat R ; but as soon as the battery is taken off at the distant end and the wire put to ground the home battery splits through magnets $S R$ and $S R'$ and coils C and C' , causing coil C or C' to act on needle n and through it on magnets m or m' up to a difference of resistance in the main and artificial line equal to the strength at which retractile springs j and j' have been set, which would normally be one-fourth of the strength of the main battery, as that is the lowest division of battery made in quadruplex circuits, and as the difference of resistance at which mutilated signals are caused is much less than this equivalent there is quite a wide margin between the resistance at which coils C C' would be able to act on rheostat R and the resistance at which magnets $S R$ $S R'$ would prevent them from acting by causing armature sa to break the local circuit controlled by needle n . It can therefore be seen that it is possible for a person at one end of a circuit to balance the instruments at the other end of the circuit by merely cutting off his own battery and putting the wire to ground, thus saving much valuable time and preventing annoying delays.

Now, having described the action of the different parts on or with each other, what I claim as new, and desire to secure by Letters Patent, is—

1. In a multiplex-telegraph circuit, the combination of a shunting instrument, consisting of electromagnets, an armature, common to said magnets, contact-arms, a contact-post, separating the latter, and the adjustable springs, coöperating with said contact-arms, with the controlling instrument and its local circuit, and means actuated by said local circuit, for varying the resistance of the artificial line, substantially as set forth.

2. In a multiplex-telegraph circuit, the combination of a shunting instrument, consisting of electromagnets, an armature, common to said magnets, the contact-arms, a contact-post, separating the latter, and the adjustable springs, coöperating with said contact-arms, with the controlling instrument and its local circuit, and the main and artificial line, and means actuated by said controlling instrument, for varying the resistance of the artificial line.

3. In a multiplex-telegraph circuit, the combination of a shunting instrument, consisting of electromagnets, an armature, common to said magnets, contact-arms, contact-post, and 5 adjustable springs, with the controlling instrument, its local circuit, the local magnets, in said local circuit, and the automatic rheostat, all substantially as and for the purpose set forth.
- 10 4. In a multiplex-telegraph circuit, the combination of a shunting instrument, consisting of electromagnets, an armature, common to said magnets, the contact-arms, a post, separating the latter, and the adjustable springs, 15 coöperating with said contact-arms, with the controlling instrument and its local circuit, the main battery, the receiving instruments, the main and artificial line and condensers, and means in said artificial line, operated by 20 said controlling instrument for varying the resistance of the artificial line, substantially as set forth.
5. In a multiplex-telegraph circuit, the combination of a controlling instrument, having coils of wire, a needle, common to said coils 25 and pivoted to an electromagnet, local contact-stops, for said needle; and said magnet, connected in the artificial line, with the local circuit, the local magnets, in said circuit, the main battery, the main and artificial line, and 30 means in said artificial line for so adjusting the resistance of the latter, that the resistance of the main line and artificial line are always equal, all substantially as and for the purpose set forth.

35 In testimony whereof I have signed my name to this specification, in the presence of two subscribing witnesses, this 15th day of November, 1901.

LAWRENCE A. McCARTHY.
